UNITED STATES PATENT OFFICE

JAMES R. MCWANE, OF BIRMINGHAM, ALABAMA, ASSIGNOR TO MCWANE CAST IRON PIPE COMPANY, OF BIRMINGHAM, ALABAMA, A CORPORATION OF ALABAMA

APPARATUS FOR MOLDING CAST IRON PIPE AND THE LIKE

Original application filed March 19, 1928, Serial No. 262,683. Divided and this application filed January 14, 1932. Serial No. 586,616.

This invention relates to improvements in apparatus for molding cast iron pipe and the like and, among other objects, aims to provide an improved pattern plate so made as to prevent "ratting" or a sticking of the sand along the edges of the pattern, which results in an imperfect mold.

The present application is a division of my pending application, Serial No. 436,751, filed March 18, 1930, allowed November 19, 1931, which in turn was a division of my application, Serial No. 262,683 filed March 19, 1928, now Patent No. 1,765,021, dated June 17, 1930.

Referring to the accompanying drawing showing a preferred embodiment of the invention:—

Fig. 1 is an elevation of a portion of a jolt rammer with the pattern plate thereon, the pattern being in section, and a flask section shown above the pattern plate in cross section and ready to be rammed; and

Fig. 2 is a sectional view, on an enlarged scale, of one wall of a flask section and one pattern shown adjacent said wall, together with part of the jolt rammer.

To speed up production and to economize in the manufacture of cast iron pipe and the like, when made by the green sand, horizontal casting process, it is highly desirable to employ the jolt ramming machine. To use this ramming apparatus successfully, it is necessary to employ "pattern plates" or "match plates". Such pattern plates have one-half of the pattern secured to them and are so made as to permit lifting of the flask sections off them after the jolt ramming. In the process of molding, each pattern plate in one operation forms one-half of one or more pipe molds and these halves (the flask sections) are subsequently matched together, with the cores properly placed in the molding space to make the complete mold.

In so using a pattern plate, particularly when the mold is very long, say about 20 feet, it is very difficult to prevent what is called "ratting", this being a sticking of the sand along the edges of the pattern, when lifted, which results in an imperfect mold. It will be readily understood that "ratting"

is much more easily prevented when the pattern is dropped through the stripping plate away from the mold, as in the old process, than it is when the flask section, with the molds formed therein, is lifted from a stationary pattern attached to the pattern plate. The present invention provides a pattern plate so made as to give a "perfect lift", that is, a clean separation of the mold from the pattern plate, without injury to or misshaping of the mold.

Referring specifically to the drawing, there is shown, in Fig. 1, the drag section 10 of a multiple pipe flask, together with part of a jolt ramming machine, said flask being described and claimed in Patent No. 1,765,021 and also in the parent application, Serial No. 436,751. The drag section is shown attached to a pattern plate 11 on the surface of which is secured a plurality of half pipe patterns 12. In Fig. 2, which shows an enlarged section of those portions of the pattern plate, pattern and flask with which the present application is most intimately related, there is shown a portion of the pattern plate 11, one of the half patterns 12, and a portion of the adjacent side wall 13 of the drag. The side wall has a flat inner fillet 14, the purpose of which is to direct the pressure on the sand toward the side edge of the pattern during the ramming, and to support the sand when the drag is lifted from the pattern. The sides of the pattern, at their junctions with the pattern plate, are shown as having slightly flattened surfaces 15, inclined slightly toward each other. The taper and dimensions of the surfaces 15 are greatly exaggerated in the drawing, so that such surfaces may be seen. The extent of flattening is only a few thousandths of an inch, so that it cannot be seen by the untrained eye. The effect is that the sand will be packed more tightly in the narrow space between the flask wall 13 and pattern 12 than if the surfaces 15 were not provided.

It has been found by thousands of trials, carried out over a period of many months, that the sand is much better packed in the toe of the mold, and that the drag can be

removed without any "ratting", when the flattened surfaces 15 are provided. It has also been found that when the metal is cast, the flattened portion of the sand mold, being 5 of a softer consistency, than the more highly compressed sand in less restricted parts of the mold, is compressed very slightly by the heavy molten metal, thus compensating for the flattened portion of the mold and forming 10 an annular casting of uniform thickness.

Obviously, the present invention is not restricted to the particular embodiment thereof herein shown and described.

What I claim is:—

- 15 1. A pattern plate for molding cast iron pipe and the like having a pattern part on its face; said pattern part having plane vertically tapered surfaces instead of curved surfaces at and near its junction with the face 20 and extending a sufficient distance from said junction to permit a more perfect packing of the sand and afterwards a substantially perfect separation of the rammed sand in the flask from the pattern.
- 25 2. A pattern plate for molding cast iron pipe and the like having a half-round pattern secured thereto, and having very slightly flattened cut-away portions at the edges of the pattern such as to permit a rammed flask 30 section to be lifted from the pattern without "ratting", all without in any way distorting the resulting casting.
- 35 3. A pattern plate for molding cast iron pipe and the like having a half round pattern whose outer surface is very slightly cut-away at its lines of juncture with the plate; the extent of flattening amounting to a few thousandths of an inch.

In testimony, that I claim the foregoing as 40 my own, I have hereto affixed my signature.

JAMES R. McWANE.
